PRECAST CONCRETE JOIST AND SLAB CONSTRUCTION

Henry O. Klotz, Bethel, Conn., assignor to The Redding Marble Company, New Haven, Conn., a corporation of Connecticut

Application September 22, 1934, Serial No. 745,079

10 Claims. (Cl. 72—68)

This invention relates to new and useful improvements in building construction and has particular relation to a precast concrete joist and slab construction.

- 5 5 An object of the invention is to provide an improved precast concrete joist and slab construction for the floors or roofs of buildings, and which construction may be used to rapidly and economically set up the floors and roofs of buildings, doing away with the necessity of setting up forms and pouring the concrete on the job and permitting the precasting of the joists and the floor or roof construction in a shop and then assembling on the job.
- 10 15 Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.
- 20 25 In the drawing:

Fig. 1 is a plan view of a portion of a floor embodying the invention, a part of the wooden flooring being omitted;

Fig. 2 is a sectional view thereof, the view being taken substantially along the plane of the line 2—2 of Fig. 1;

Fig. 3 is a detail sectional view, on an enlarged scale, the view being taken substantially along the plane of the line 3—3 of Fig. 1;

Fig. 4 is an enlarged detail sectional view taken substantially along the plane of the line 4—4 of Fig. 1;

Fig. 5 is an enlarged sectional view taken substantially along the plane of the line 5—5 of Fig. 2, parts of the joist being broken away;

Fig. 6 is an enlarged detail sectional view taken substantially along the line 6—6 of Fig. 1, and showing the joint at the adjacent transverse edges of a pair of meeting slabs;

Fig. 7 is a detail view illustrating the construction of the longitudinal edges of the slabs;

Fig. 8 is a view similar to Fig. 4 but illustrating the invention when wooden flooring is not used; and,

Fig. 9 is a sectional view illustrating a further slight variation.

In the drawing the invention is shown as used in constructing of the floor of a building although it will be understood that it may also be used in constructing the roof of a building. According

to the present invention precast reinforced concrete joists 10 are used to support precast reinforced concrete slabs 11 so that no forms or the like are required at the point of construction of a building, all of the joists and slabs having been cast in a shop. As here disclosed, the slabs 11 are cast of concrete or similar material suitably reinforced and are of a width corresponding with the spacing of wooden sleepers 12 to which the wooden flooring 13 is nailed. The length of the 10 slabs is such that when the center of a slab is on one joist the respective ends of that slab rest on the adjacent joists to the right and left of the first mentioned joist. Further, the slabs are arranged in staggered relation so that the transverse joints in a floor or roof construction do not align and this is fully illustrated in Fig. 1 wherein in the joints at the transverse ends of the slab A are designated 14 and 15 while the joint at one transverse end of the slab B is shown at 16.

As shown, the joists 10 are in the form of I-beams cast from concrete and each joist includes lower and upper longitudinally extending reinforcing rods 17 and 18 and they may be tied together in any suitable manner. Partially embedded in and extending above the upper sides of the joist are stirrups 19 and such stirrups are anchored in the respective joists, as for example and preferably by having their lower ends formed into eyes 20 wrapped about the lower 25 reinforcing bar and also by being bent laterally around and spot welded to the upper reinforcing bar 18 as at 21. It will thus be seen that these stirrups provide means for tying the reinforcing rods 17 and 18 together making a 30 strong, rigid and unitary construction, additional tying means may be provided between the stirrups if their spacing is too great or if additional tying means is found necessary or desirable. The stirrups may be otherwise anchored in the 35 joists if desired. From the drawing it will be clear that the stirrups 19 are in the form of rods and that the upper end of each stirrup is screw threaded to receive a nut 22 below which may be located a washer 35.

The wooden sleepers 12 above referred to are received in grooves and to provide such grooves the longitudinal edges of the slabs are rabbeted as shown at 23 in Fig. 7. It will be evident that when the longitudinal edges of two slabs are placed together as in Fig. 4 the two rabbets 23 form a tapered groove to receive a transversely wedge-shaped wooden sleeper 12. The spacing of the stirrups 19 is such that they enter the 40 grooves formed by the rabbets 23 and the upper 45

ends of the stirrups extend into the wooden sleepers 12 and the latter are counterbored as at 24 to accommodate the nuts 22 and washers 35.

With this arrangement it will be noted that 5 the nuts and the upper threaded ends of the stirrups are below the upper surfaces of the wooden sleepers so that the stirrups and nuts will not interfere with the laying of the wooden flooring 13. Usually a second or finishing flooring (not 10 shown) is applied on top of the flooring 13. Preferably the sleepers extend slightly above the upper surfaces of the slabs 13 so that there will be a small space 25 below the wooden flooring. It 15 will be apparent that the sleepers may be drawn 20 against the portions of the slabs forming the bottom walls of the grooves in which the sleepers are located, on tightening of the nuts 22, and that when the sleepers are clamped against such 25 portions of the slabs the sleepers are securely tied down making a tight closed joint between 20 the slabs, and that the slabs themselves are tied down onto the joists.

On its under side intermediate its ends each 25 slab is provided with a transverse recess or groove 26 for the reception of the upper edge of a joist and at its transverse edge portions each slab is provided with one-half of such groove or recess as at 27. With this arrangement when 30 the slabs are in place the transverse joints between adjacent slabs are made up as best shown in Fig. 6. There it will be noted that the recesses 27 in the adjacent portions of a pair of slabs 35 form a groove receiving the upper edge of a joist 10. The transverse edges of the slabs are preferably inclined slightly providing a tapered joint which may be filled with grout as at 28 (see particularly Fig. 6).

If a cement or terrazzo floor is to be used then the arrangement is as shown in Fig. 8 where the 40 joist 10 and the slabs 11 are of the construction already described. The wooden sleepers are omitted when the cement or terrazzo floor is to be used, and in place of such sleepers metal strips 29 are placed in the grooves formed between 45 the longitudinal edges of the slabs, and the stirrups 19 pass through such strips whereby on tightening the nuts 22 of such stirrups the strips will be clamped against the edge portions of the slabs and the latter will be clamped to 50 the joists. Thereafter, the concrete or terrazzo floor 30 may be poured on top of the slabs filling in the grooves at the longitudinal edges thereof, or the grooves may be nearly filled with grouting 55 31 prior to the pouring of the floor 30.

Fig. 9 shows a further slight variation and in this figure a wooden sleeper 12 is shown in place in a groove formed between the adjacent longitudinal edges of a pair of slabs 11 and the wooden flooring 13 is secured to said sleeper. However, 60 in Fig. 9 the joist is shown as in the form of a metal beam 32. Carried by such beam and extending through the groove and into the sleeper is a stirrup in the form of a bolt 33 on the upper end of which is threaded a nut 34 between 65 which and the sleeper there may be interposed a washer 35 as shown. On tightening of the nut 34 the sleeper will be clamped against the portions of the slabs forming the bottom of the groove and the slabs will be clamped against the 70 joist 32.

It will now be understood that according to the present invention the joists and slabs are all precast so that the use of forms is not required at the construction site. When the joists are 75 in place the slabs are rested on the joists pref-

erably in such staggered relation that the transverse edges of laterally adjacent joists do not align, and when the slabs are positioned the rabbeted longitudinal edges of the adjacent slabs form grooves extending transversely of the joists. It will also be clear that the upper ends of the stirrups carried by the joists will be extending into such grooves at the proper points, and when wooden flooring is to be laid wooden sleepers properly drilled and counterbored for the reception of the upper ends of the stirrups and the nuts 22 are disposed in the grooves with the stirrups extending into them.

If desired, washers 35 may be disposed about the stirrups below the nuts 22 and on tightening 15 of the nuts the sleepers are firmly tied in place and tie the slabs to the joists. Fig. 8 clearly illustrates that when a concrete or terrazzo floor is to be laid the wooden sleepers are omitted and the slabs are tied or clamped to the joists by 20 the stirrups acting through metal strips 29. Fig. 9 illustrates the manner in which the principles of the invention may be employed when a metal joist is used, and in this figure it will be apparent that the stirrup 33 ties the wooden sleeper 12 in 25 place and also ties the slabs to the joist. The threaded stirrups in the preferred form originate from, or that is are firmly secured to, the main reenforcement for the joists so are firmly anchored in them and form part of the reenforcement. The reinforced slabs are constructed in a manner to form receiving recesses at the bottom to fit over the joists, and on the top a continuous recess is formed at right angles to the joists that will allow a wooden sleeper to be bolted 30 to the threaded stirrups cast in the joists, the advantages being that said wooden sleeper will act as a continuous tie and separator, and function as a nailing strip to fasten finished wood flooring. 35

Having thus set forth the nature of my invention, what I claim is:

1. A roof or floor construction comprising supporting joists, precast cementitious slabs on said joists, a pair of said slabs having their adjacent edges rabbeted providing a groove, stirrups anchored by and extending above said joists and entering said groove, a member in and extending longitudinally of said groove, and means on said stirrups to clamp said member against the portions of the slabs forming the bottom of the groove and clamping said slab portions against the joists.

2. A roof or floor construction comprising supporting joists, precast cementitious slabs on said joists, a pair of said slabs having their adjacent edges rabbeted providing a groove, stirrups anchored by and extending above said joists and entering said groove, a wooden sleeper in and extending longitudinally of said groove, and means on said stirrups to clamp said wooden sleeper against the portions of the slabs forming the bottom of the groove and clamping said slab portions against the joists.

3. A roof or floor construction comprising supporting joists, cementitious slabs on and having edges extending transversely of said joists, said slabs having their adjacent such edges rabbeted providing grooves extending transversely of said joists, stirrups anchored by and extending above said joists and entering said grooves, members in and extending longitudinally of said grooves, and means on said stirrups to clamp said members against the portions of the slabs forming the bottoms of said grooves and clamping said slab portions against the joists.

4. A roof or floor construction comprising supporting joists, cementitious slabs on and having edges extending transversely of said joists, said slabs having their adjacent such edges rabbeted 5 providing grooves extending transversely of said joists, stirrups anchored by and extending above said joists and entering said grooves, wooden sleepers in and extending longitudinally of said grooves, and means on said stirrups to clamp said 10 wooden sleepers against the portions of the slabs forming the bottoms of said grooves and clamping said slab portions against the joists.
5. A roof or floor construction comprising supporting joists, cementitious slabs on and having edges extending transversely of said joists, said slabs having their adjacent such edges rabbeted 15 providing tapered grooves extending transversely of said joists, stirrups anchored by and extending above said joists and entering said grooves, tapered wooden sleepers in and extending longitudinally of said grooves, and means on said stirrups to clamp said sleepers against the portions of the slabs forming the bottoms of said grooves and clamping said slab portions against the joists. 20
6. A roof or floor construction comprising cementitious supporting joists, cementitious slabs on and having edges extending transversely of said joists, said slabs having their such edges rabbeted 25 providing grooves extending transversely of said joists, stirrups partially embedded in and extending above said joists and entering said grooves, members in and extending longitudinally of said grooves, and means on said stirrups to clamp said members against the portions of the slabs forming the bottoms of said grooves and clamping said slab portions against the joists. 30
7. A roof or floor construction comprising reinforced cementitious supporting joists, cementitious slabs on and having edges extending transversely of said joists, said slabs having their such edges rabbeted 35 providing grooves extending transversely of said joists, stirrups partially embedded in and secured to the reenforcement of and extending above said joists and entering said 40
- grooves, members in and extending longitudinally of said grooves, and means on said stirrups to clamp said members against the portions of the slabs forming the bottoms of said grooves and clamping said slab portions against the joists. 5
8. A roof or floor construction comprising cementitious joists having upper and lower longitudinally extending reenforcing bars, cementitious slabs on and having edges extending transversely of said joists, said slabs having their such edges rabbeted 10 providing grooves extending transversely of the joists, stirrups partially embedded in and extending above the joists and entering said grooves, said stirrups being bent about the lower and welded to the upper reenforcing bars of the joists, members in and extending longitudinally of said grooves, and means on said stirrups to clamp said members against the portions of the slabs forming the bottoms of said grooves and clamping said slab portions against the joists. 15
9. A roof or floor construction comprising supporting joists, cementitious slabs on said joists, a pair of said slabs having their adjacent edges rabbeted 20 providing a groove, stirrups anchored by and extending above said joists and entering said groove, a wooden sleeper in and extending longitudinally of said groove, and nuts threaded on the upper ends of said stirrups to clamp said wooden sleeper against the portions of the slabs forming the bottom of the groove and clamping 25 said slab portions against the joists. 30
10. A roof or floor construction comprising supporting joists, cementitious slabs on and having transverse recesses receiving the upper edges of said joists, a pair of said slabs having their adjacent edges rabbeted 35 providing a groove, stirrups anchored by and extending above said joists and entering said groove, a member in and extending longitudinally of said groove, and means adjustable on said stirrups to clamp said member against the portions of the slabs forming the bottom of the groove and clamping said slab portions against the joists. 40
